1

Latin name of the genus and species of the plant claimed:
Chrysanthemum×morifolium.
Varietal denomination: 'Syngigi Yel'.

BACKGROUND OF THE NEW PLANT

The present invention comprises a new *Chrysanthemum*, botanically known as *Chrysanthemum×morifolium*, and hereinafter referred to by the variety name 'Syngigi Yel'.

'Syngigi Yel' is a product of a planned breeding program. The new cultivar has small, bold yellow flowers, strong and stiff peduncles, medium green foliage, and compact and mounded plant habit.

'Syngigi Yel' originates as a natural whole plant mutation of 'Yogigi Snow', U.S. Pat. No. 21,783, and was discovered and selected by the inventor as a single flowering plant within a population of the parent cultivar in a controlled breeding program in Alva, Fla., in November 2004. The parent cultivar 'Yogigi Snow' has white flowers.

The first act of asexual reproduction of 'Syngigi Yel' was accomplished when vegetative cuttings were propagated from the initial selection in December 2004 in a controlled environment in Alva, Fla.

BRIEF SUMMARY OF INVENTION

Horticultural examination of plants grown from cuttings of the plant initiated in December 2004, and continuing thereafter, has demonstrated that the combination of characteristics as herein disclosed for 'Syngigi Yel' are firmly fixed and are retained through successive generations of asexual reproduction.

'Syngigi Yel' has not been observed under all possible environmental conditions. The phenotype may vary significantly with variations in environment such as temperature, light intensity and day length.

Plant Breeder's Rights for this cultivar were applied for in Canada on Oct. 30, 2009 (09-6793) and in CVPO on Jan. 29, 2010 (2010/0195). 'Syngigi Yel' has not been made publicly available more than one year prior to the filing of this application.

(57) ABSTRACT

A new *Chrysanthemum* plant named 'Syngigi Yel' particularly distinguished by the small, bold yellow flowers; strong and stiff peduncles, medium green foliage, and compact and mounded plant habit.

1 Drawing Sheet**2**

The following traits have been repeatedly observed and are determined to be basic characteristics of the new variety. The combination of these characteristics distinguishes this *Chrysanthemum* as a new and distinct variety.

5

BRIEF DESCRIPTION OF THE PHOTOGRAPHS

The accompanying photographic drawing shows typical flower and foliage characteristics of 'Syngigi Yel' with colors being as true as possible with an illustration of this type. The photographic drawing shows a flowering potted plant of the new variety, and a close-up of the flowers.

DETAILED BOTANICAL DESCRIPTION

15

The plant descriptions, measurements and aforementioned photographs were taken in Gilroy, Calif. in May under natural light. These plants were grown in a greenhouse under conditions which approximate those generally used in commercial potted *Chrysanthemum* production in Gilroy, Calif. These plants used in the photograph and descriptions were about 12-14 weeks of age.

Color references are made to The Royal Horticultural Society Colour Chart (R.H.S.) 2001.

TABLE 1**DIFFERENCES BETWEEN THE NEW VARIETY 'SYNGIGI YEL'
AND A SIMILAR VARIETY: 'JANICE' (U.S. Plant Pat. No. 9,817)**

	'Syngigi Yel'	'Janice' (U.S. Plant Pat. No. 9,817)
Flower color:	More yellow/less gold	More gold
Flower size:	Smaller	Larger
Plant habit:	Rounded and more compact	Less round/compact

Plant:

Form, growth and habit.—Herbaceous decorative garden-type. Stems upright and outwardly spreading on short, mounded and compact plants, with strong and stiff branches.

Plant height.—About 10 cm.

30

35

40

<i>Plant height (inflorescence included).</i> —12-14 cm.		<i>Total diameter of 'disc'.</i> —0.5-0.7 cm.
<i>Plant width.</i> —25 cm.		<i>Receptacle height.</i> —0.2 cm.
<i>Garden performance and tolerance to weather.</i> —Very good.		<i>Receptacle diameter.</i> —0.5 cm.
<i>Crop time to flowering.</i> —About 10 weeks.		<i>Ray florets:</i>
Roots:		<i>Average quantity of florets.</i> —About 135 in numerous whorls.
<i>Number of days to initiate roots.</i> —4 days at about 22 degrees C.	5	<i>Color of florets, upper surface.</i> —RHS 6B maturing to about RHS 9A to RHS 9B.
<i>Number of days to produce a rooted cutting.</i> —7-10 days at 22 degrees C.	10	<i>Lower surface.</i> —RHS 8B.
<i>Type.</i> —Fine, fibrous, free branching.	15	<i>Length.</i> —1.7-2.1 cm.
<i>Color.</i> —RHS N155B but whiter.		<i>Width.</i> —0.6-0.7 cm.
Foliage:		<i>Shape.</i> —Obovate.
<i>Arrangement.</i> —Alternate.		<i>Apex shape.</i> —Irregularly emarginated to praemorse.
<i>Immature, leaf color, upper surface.</i> —RHS 137A but a little darker.	15	<i>Margin.</i> —Entire.
<i>Lower surface.</i> —Closest to RHS N138B.		<i>Texture, upper surface.</i> —Papillose.
<i>Mature, leaf color, upper surface.</i> —RHS 137A but a little darker.		<i>Lower surface.</i> —Papillose.
<i>Lower surface.</i> —Closest to RHS N138B.		<i>Disc florets:</i>
<i>Length.</i> —4.0-4.5 cm.	20	<i>Average quantity of florets.</i> —About 50.
<i>Width.</i> —2.9-3.5 cm.		<i>Color of florets.</i> —Close to RHS 144D with a RHS 13A apex.
<i>Shape.</i> —Ovate.		<i>Length.</i> —0.4-0.5 cm.
<i>Base shape.</i> —Attenuate.		<i>Width.</i> —0.1 cm.
<i>Apex shape.</i> —Mucronulate.		<i>Shape.</i> —Tubular, elongated.
<i>Margin.</i> —Serrate.	25	<i>Apex shape.</i> —Acute, 5 pointed.
<i>Texture, upper surface.</i> —Bifid T-shaped hairs.		<i>Phyllaries:</i>
<i>Lower surface.</i> —Bifid T-shaped hairs.		<i>Quantity.</i> —About 20.
<i>Color of veins, upper surface.</i> —RHS 146D.		<i>Color, upper surface.</i> —RHS 137C.
<i>Color of veins, lower surface.</i> —RHS 146D.		<i>Lower surface.</i> —RHS 137C.
<i>Petiole color.</i> —RHS 146D.		<i>Length.</i> —0.4-0.6 cm.
<i>Length.</i> —0.9-1.1 cm.	30	<i>Width.</i> —0.1-0.15 cm.
<i>Diameter.</i> —0.1 cm.		<i>Shape.</i> —Lanceolate.
<i>Texture.</i> —Bifid T-shaped hairs.		<i>Apex shape.</i> —Acute.
Stem:		<i>Based.</i> —Fused.
<i>Quantity of main branches per plant.</i> —6-7.		<i>Margins.</i> —Entire; with papery edges.
<i>Color of stem.</i> —Closest to RHS 146D.		<i>Texture, upper surface.</i> —Smooth, glabrous.
<i>Length of stem.</i> —9-11 cm.	35	<i>Lower surface.</i> —Bifid T-shaped hairs.
<i>Diameter.</i> —0.3-0.4 cm.		<i>Reproductive organs:</i>
<i>Length of internodes.</i> —0.4-0.7 cm.		<i>Found on both floret types.</i> —
<i>Texture.</i> —Bifid T-shaped hairs.		<i>Pistil.</i> —1.
<i>Color of peduncle.</i> —RHS 144A.	40	<i>Length.</i> —0.4-0.5 cm.
<i>Length of peduncle.</i> —4-5 cm.		<i>Style color.</i> —RHS 1C with a little more green.
<i>Peduncle diameter.</i> —0.1 cm.		<i>Style length.</i> —0.3-0.4 cm.
<i>Texture.</i> —Bifid T-shaped hairs.		<i>Stigma color.</i> —RHS 3A.
Inflorescence:		<i>Stigma shape.</i> —Bi-parted.
<i>Type.</i> —Compositae type, solitary inflorescences (decorative-type) borne terminally above foliage, ray florets arranged acropetally on a capitulum.	45	<i>Ovary color.</i> —Not observed.
<i>Natural flowering season.</i> —About mid-September.		<i>Found on only disc florets.</i> —
<i>Quantity of inflorescences per plant.</i> —46-50 and numerous buds.		<i>Stamens.</i> —1.
<i>Lastingness of individual blooms on the plant.</i> —About 4 weeks.	50	<i>Color of filaments.</i> —RHS 155C.
<i>Fragrance.</i> —Slightly spicy.		<i>Length filaments.</i> —0.1-0.2 cm.
BUD (just when opening/showing color):		<i>Anther color.</i> —RHS 13B.
<i>Color.</i> —RHS 4B with a RHS 6A apex.		<i>Anther length.</i> —0.1 cm.
<i>Length.</i> —0.7-0.9 cm.		<i>Anther shape.</i> —Ovate.
<i>Width (cm).</i> —0.9-1.0 cm.		<i>Color of pollen.</i> —RHS 15B.
<i>Shape.</i> —Oblate.		<i>Pollen amount.</i> —About average.
Immature inflorescence:		<i>Fertility/seed set.</i> —Has not been observed on this hybrid.
<i>Diameter.</i> —3.0-3.2 cm.	55	<i>Disease/pest resistance:</i> Disease/pest resistance has not been observed on this hybrid.
<i>Color of ray florets, upper surface.</i> —RHS 6A.		
<i>Lower surface.</i> —RHS 6C.		What is claimed is:
Mature inflorescence:		1. A new and distinct variety of <i>Chrysanthemum</i> plant named 'SyngigiYel' substantially as illustrated and described herein.
<i>Diameter.</i> —4.0-4.2 cm.		
<i>Depth.</i> —1.5 cm.		

UNITED STATES PATENT AND TRADEMARK OFFICE
CERTIFICATE OF CORRECTION

PATENT NO. : PP22,514 P2
APPLICATION NO. : 12/925038
DATED : February 21, 2012
INVENTOR(S) : Smith
